UNITED STATES PATENT OFFICE.

EDWARD E. DUNNEGAN, OF PINE BLUFF, ARKANSAS.

TOY GUN.

Application filed April 28, 1927. Serial No. 187,254.

The invention aims to provide an exceptionally simple and inexpensive, yet an effective toy gun, for the purpose of shooting rubber bands, and with this object in view, 5 the invention resides in the novel subject matter hereinafter described and claimed, the description being supplemented by the accompanying drawing.

Fig. 1 is a side elevation.

10 Fig. 2 is a top plan view.

Fig. 3 is a central vertical, longitudinal section partly in elevation.

Fig. 4 is a transverse section on line 4—4 of Fig. 3.

15 The drawing above briefly described, illustrates the preferred form of construction, and while this construction will be herein specifically described, it is to be understood that within the scope of the invention as 20 claimed, variations may be made. Moreover, while wood is preferable in the construction of some parts of the device, metal or other desired material or materials could well be used.

25 The numeral 5 designates a barrel having a downwardly projecting hand grip 6 at its rear end, the upper end of said hand grip being formed with an opening 7 from front to rear, while the lower portion of this hand 30 grip is provided with a rearwardly opening socket 8.

35 Behind the barrel 5 and the hand grip 6, is a vertically disposed hand lever 9, said lever being forwardly thickened at its upper end to provide a fulcrum portion 10 below the opening 7, and a band-gripping portion 11 above said opening, said portion 11 being 40 cooperable with the rear end of the barrel 5, to hold a rubber band 12 which is passed around the front end of the barrel 5 and 45 is longitudinally stretched. If desired or necessary, a small piece of sand paper or the like 13 may be secured either to the rear end of the barrel 5 or to the band-gripping portion 11, to insure that the stretched rubber band shall be effectively held.

50 A tension spring 14 extends longitudinally under the barrel 5 and has its front end anchored thereto, for instance, by a screw eye 15. The rear end of this spring passes loosely through the opening 7 and is secured to the hand lever 9, preferably by a screw eye 16. Thus, the spring 14 acts to not only hold the hand lever 9 in band-gripping position, but forms effective means for connecting said hand lever with the remainder 55

of the gun. To prevent lateral swinging of this hand lever about the spring 14 as a pivot, its lower portion is provided with a forwardly projecting pin 17 which is slidably received in the socket 8.

At 18, I have shown a rigid arched yoke through which the rubber band 12 passes loosely, said yoke having its ends disposed at opposite sides of and secured to the barrel 5, while its crown portion is spaced above said barrel. In case the rubber band should slip from the front end of the barrel, this yoke prevents it from flying rearwardly and possibly injuring the child using the gun.

70 In loading the gun, a rubber band 12 is passed through the yoke 18 and its opposite sides are pinched together and positioned between the rear end of the barrel 5 and the band-gripping portion 11 of the lever 9, it 75 being of course necessary to rock this lever about its fulcrum portion 10 to insert the band. After such insertion, release of the lever causes the spring 14 to tightly hold the band-gripping portion 11 in cooperable 80 relation with the rear end of the barrel 5, thus tightly anchoring the rubber band. This band may then be stretched and passed around the front end of the barrel as seen in Fig. 1. When the hand lever 9 is pushed 85 forwardly by tightening the grip upon the hand grip 6, the rear end of the stretched rubber band is released, with the result that it will be forwardly impelled under the influence of its own resiliency. Should the 90 front end of the band slip from the barrel, it cannot backfire from the gun, due to the provision of the yoke 18.

95 It will be seen from the foregoing that I have produced an exceptionally simple and inexpensive construction, yet one which will give a great deal of amusement.

I claim:—

100 1. A toy gun for shooting rubber bands, comprising a barrel, a hand grip projecting downwardly therefrom, said hand grip having an opening from front to back at its upper end and being formed with a rearwardly-opening socket below said opening, a vertical hand lever behind said barrel and 105 hand grip, said lever having a fulcrum portion below said opening and a band-gripping portion above said opening, said band-gripping portion being co-operable with the rear end of said barrel, a coiled tension 110 spring disposed under said barrel and at its front end anchored thereto, the rear end

of said spring being passed through said opening and secured to said hand lever to connect the latter with the hand grip and to hold said lever in hand-gripping position, 5 and a pin projecting forwardly from said hand lever and slidably received in the aforesaid socket to prevent lateral turning of the hand lever about the spring.

2. A toy gun comprising a barrel, releasable means at the rear end of said barrel 10 for holding a rubber band stretched between said means and the front end of said barrel, and barrel-carried means through which the band passes loosely, said barrel-carried 15 means preventing backfiring of the band

should it slip from the front end of the barrel.

3. A toy gun comprising a barrel, releasable means at the rear end of said barrel 20 for holding a rubber band stretched between said means and the front end of said barrel, and a rigid arched yoke through which the band passes loosely, said yoke being secured to the barrel and having its crown upwardly spaced therefrom, said yoke preventing 25 backfiring of the band should it slip from the front end of the barrel.

In testimony whereof I have hereunto affixed my signature.

EDWARD E. DUNNEGAN.
